BAND STRAPPING MACHINE

George Mortimer, Westcliff-on-Sea, England

Application June 18, 1936, Serial No. 85,913
In Great Britain September 17, 1934

4 Claims. (Cl. 81—9.1)

This invention relates to band strapping machines, such as are used for tensioning strapping bands and for uniting the overlapping ends thereof. The chief object of the present invention is to provide a simple and small machine which will be easy to operate and efficient in use.

The band strap sealing machine according to the present invention comprises essentially one or more punches which are adapted to punch down tongues from the overlapped ends of the band, in combination with one or more slide members adapted to move under the overlapped ends of the band to turn over the tongues after the punches have been retracted effectively to seal the overlapping ends of the band together.

Two spaced punches and two sliding plates are preferably provided, these parts being all operated in the desired sequence by means of a single operating lever or the like.

A cutter is also provided in the machine, this cutter also being adapted, when operated, to seal the free end of the band strap to the part of the band lying under the same, thereby avoiding all possibility of the end of the band catching in other cases or tearing the hands of persons handling the strapped box or case.

Means are, of course, provided to tension the band prior to sealing and said tensioning means are preferably so constructed and arranged to slip should the strain on the band become excessive.

In order that this invention may be the more clearly understood and readily carried into effect, I will proceed to describe the same with reference to the accompanying drawings, which illustrate by way of example and not of limitation one convenient embodiment of this invention, and in which:—

Figure 1 is a front elevation of the machine, and

Figure 2 is a plan view of the same.

Figure 3 is a transverse vertical section through the sealing part of the machine.

Figure 4 is a longitudinal vertical section illustrating the manner in which the first part of the sealing operation is performed.

Figure 5 is a sectional under plan view on line 5—5 of Figure 4, showing the inoperative position of the slide members, and

Figure 6 is a similar view showing the slide members operated to complete the seal.

Figure 7 is a transverse vertical section through the cutter and its operating lever showing also the manner in which the gripper is operated.

Figure 8 is a longitudinal sectional view

through the cutter showing the method of sealing the free end of the band.

Figures 9 and 10 are two views of the tensioning device illustrating the two main positions thereof, and

Figure 11 is an end elevation of the machine.

Figures 12, 13 and 14 are views showing the various stages of the seal.

Referring now to the drawings, the device comprises a base 20 on which the whole device stands, this base having cast integrally with it (or mounted thereon) a main bearing block 21. The block 21 towards one end of the same is provided with a slot 22 extending from front to back and within this slot is mounted, on a pin 23, the handle 24 which operates the sealing part of the machine. The block 21 is also slotted as at 25 from front to back to allow for the mounting, on a pin 26, of the cutter operating handle 27.

A groove 28 is provided at the front of the machine in the usual manner to receive the overlapped parts of the band to be sealed.

Describing now the sealing part of the machine, the seal is, as above stated, effected by punching down tongues from the overlapped parts of the band and then turning them over, in opposite directions, on the underside of the overlapped parts of the band. The punching member comprises a plate 29 having at its lower end two spaced tapering punching dies 30, this plate being slidably located in a recess in the main block 21, which recess is covered by a cover plate 31. The operating handle 24 for the sealing part of the machine is provided with a forwardly projecting lug 32 which is located in a slot 32' in the plate 29 so that, when the handle is swung backwards and forwards, the plate 29 is raised and lowered.

The dies 30 co-operate with corresponding female die parts or recesses 33 in a cover plate 34, which covers a recess 35 in the base of the machine. In this recess is slidably mounted a slide block 36 having on its upper surface a recess 37 in which engages a lug 38 on the operating handle 24, this lug being so arranged that, when the operating handle 24 is swung rearwardly, the slide block is moved forwardly towards the front of the machine. Pivotedly mounted on pins 39 at the rear end of the slide block and on the under side of the same are two arms 40, a blade spring 41 being disposed between the slide block 36 and the arms 40.

These arms are cut away at their forward ends to embrace a fixed pin 42 carried by the main block 21 and are located between shoulders 43

in the recess. At the front end the shoulders are cut away to form cam surfaces 44 and the arms are provided with co-operating cam projections 45.

- 5 Describing now the operation of the sealing portion of the machine, the operating handle 24 has three positions (see Figure 3), being held by a spring-pressed ball 46 carried by the main block 21 in the centre or inoperative position. The 10 first operation is to pull the operating handle 24 forwardly. This is without effect on the slide block 36 since the lug 38 on the operating handle merely moves idly back in the recess 37 in the slide block. Forward movement of the handle 24, 15 however, by reason of the engagement of the lug 32 thereon with the recess in the slot 32' in the die plate 29 forces the said plate down and punches down from the overlapped parts of the band two pairs of tongues 47 (see Figure 12). 20 The operating handle is now swung backwardly and, in moving to its operative position, raises the plate 29 and frees the dies 30 from the band. In moving still further back to the third position of the operating handle the lug 38 moves the 25 slide block forwardly causing the forward ends of the arms (which are bevelled away) first to become located under the overlapped parts of the band between the punched down tongues. Continued movement in the rearward direction of 30 the handle 24 causes the arms to move forward to such an extent that the ends of the cut away parts move past the fixed pin 42 whereupon the arms are moved apart and the forward ends thereof bearing on the punched down tongues 35 47 turn them over under the overlapped parts of the band (see Figure 13). A very effective seal is thereby made. When the operating handle 24 is returned to its centre, inoperative position the slide block 36 is withdrawn and, due to 40 the cam projections 45 on the arms engaging with the cam surfaces 44 on the shoulders 43, the arms 44 are brought together with their forward ends embracing the pins ready for the next operation.
- 45 The whole seal consisting of punching down tongues and turning them over on the underside of the band is thus effected by means of a single backward and forward movement of the operating handle 24. Of course, any number of tongues 50 may be punched down, the appropriate number of arms being provided to turn over such tongues.

Describing now the cutter device, this, as above mentioned, is operated by the handle 27 and comprises a cutter member 50 slidably mounted 55 in a suitably positioned recess in the main block 21 and slotted as at 51 to receive the forward end of the handle 27. The lower end of the member 50 is cut away so as to form a cutting edge 52 and also, between the cutting edge 52 and the sealing part of the machine, is provided 60 with a male die part 53 co-operating with a female die part or recess 54 in a cover plate 55 forming a part of the base of the machine and covering an aperture therein. This die part 53, 65 and the corresponding recess, are tapered outwardly away from the sealing part of the band for a purpose hereinafter described.

Mounted in the recess which is covered by the cover plate 55 is a gripper member 56 having a 70 locating pin 57 at the rear end, and being grooved or roughened at its forward end as at 58 to co-operate with a similarly grooved or roughened part 59 on the cover plate 55 to grip the free end of the band. A compression spring 60 is disposed between the gripper member 56 and the

cover plate 55, this spring tending to raise the gripper member. The gripper member is operated by a rod 61 located in the main block and bearing at its upper end on a suitably formed part of the cutter operating handle 27.

This rod is so arranged that, when the handle 27 is thrown right back, the rod is depressed and forces the roughened part of the gripper member 56 into engagement with the part 59 of the cover plate.

When the handle is moved forward (after the sealing has been partially effected, as hereinafter explained), the rod is free to rise under the action of the spring 60 and so the one end of the band is freed. The cutter is forced down and the cutting edge thereof co-operates with the upper edge of the gripper member to sever the band and then the die part 53 functions to seal the upper free end of the band by punching small tongues 61' down from the overlapping parts 20 of the band (see Figure 14). As the metal of the band gives slightly when the tension is released despite the sealing by the tongues 47, the tongues 61' will move slightly with respect to one another and the one tongue will bite into the sides of 25 the aperture in the other band, and hence the upper free end of the band will be effectively sealed very close to its end and all possibility of releasing the seal without cutting the band will be avoided. In order still further to prevent the 30 free end of the band damaging the hands of a person handling the box or catching in any obstruction, the cutter is shaped so as to turn down the extreme end of the band together with the underlying part of the band into a 35 groove 62 in the cover plate 55 (see 63, Figure 14).

Describing now the tensioning device, this is substantially of the known type comprising a lower knurled roller 70 and an upper knurled 40 roller 71 between which the band is passed, the upper roller 71 carrying ratchet teeth 71', which are engaged by a spring-controlled pawl 72 carried by the handle 72. Oscillation of the handle 72 will therefore cause the upper roller 71 to be advanced. 45 70 is a spring-controlled back-stop pawl. In the constructions of a tensioning device of this type heretofore proposed, the lower roller has been fixedly mounted but, in accordance with the present invention, the same is 50 carried at one end of a lever arm 73 pivoted at 74 in the main block 21, the other end of this arm being provided with an adjustable pin 75 which is forced up into engagement with the boss of the handle 72 by means of a blade spring 55 76 which bears either on a nut 77 on the pin 75, as shown, or on the underside of the lever arm 73. It will be seen that the tendency of the spring 76 is to move the lower roller away from the upper roller, it being prevented from doing 60 so by reason of the engagement of the pin 75 with the boss. The boss is, however, notched as at 78 so that, when the handle 72 is moved completely over to the right, the pin moves up into this notch and the rollers are freed. This 65 facilitates the insertion and removal of the band from the tensioning device. Further, by adjusting pin 75 the effective grip of the rollers can be adjusted and the machine can be so set that the rollers will slip if the tension becomes 70 excessive.

In use, the free end of the band is inserted under the die plate 29 and is then passed between the parts 58, 59. The band is then passed around the box, again under the die plate 29, 75

over the gripping member 56 and between the rollers 70, 71. The machine is then ready to tension and seal the band. With the cutter operating handle thrown back (and, if required, held back) so as to grip the lower band between the parts 58, 59, as above described, the tensioning handle 72 is operated to put the band under the necessary tension. With the band under tension the cutter handle 27 is taken in the right hand and held back (to keep the band gripped) and the handle 24 is taken in the left hand. Now the handle 24 is pulled forward, the handle 27 still being held back, to punch down the tongues 47. The two handles 24 and 27 are then moved first respectively backwards and forwards and then forwards and backwards. On the first backward and forward movement the tongues 47 will be turned under, as above described, the band will be severed and the free end thus made will be sealed and turned down all as above described. On the next movement, i. e., the forward and backward movement, the parts will be reset to their initial position and the band between the parts 58, 59 will be released. The tension handle 72 is thrown over to its extreme right when the machine can be removed and the box will be effectively strapped. The necessary movements of the two handles 24 and 27 are, it will be seen, absolutely natural movements which may be easily carried out. The forces work against one another and the arrangement is such that the operator is able to exert the necessary force in the easiest and simplest manner.

Many modifications may be made in the above described constructional form of machine without departing from the scope of the present invention as defined in the appended claims.

I claim:—

1. A band strap sealing machine, a block, a punch vertically movable therein and adapted to punch down a tongue from the overlapped ends of a band, means slidable horizontally within the block under the overlapped ends of the band and adapted to engage and turn the tongue over, a lever pivotally mounted in the block and having portions operatively connected to both the

punch and slidable means, said portions of the lever being located on opposite sides of the lever pivot, whereby movement of the lever in one direction operates said punch and movement thereof in the opposite direction operates said slidable means. 5

2. A band strap sealing machine as in claim 1, in which the block has a means coacting with cooperating cam surfaces on the slidable means to move said latter means laterally to turn over 10 the punched-down tongues.

3. A band strap sealing machine, a block, a punch vertically movable therein and adapted to punch down a tongue from the overlapped ends of a band, means slidable horizontally within the block under the overlapped ends of the band and adapted to engage and turn the tongue over, said means including a slidable member and cooperating movable members pivoted thereto, said movable members having cam surfaces, a 20 lever pivotally mounted in the block, lugs on said lever operatively connected to both the punch and slidable member, said lugs being located on opposite sides of said lever pivot, whereby movement of the lever in one direction operates 25 said punch and movement thereof in the opposite direction operates said slidable means, said block having a pin coacting with the cam surfaces on the movable members to move said members laterally to turn over the punched-down 30 tongue.

4. A band strap sealing machine, a block, a vertically movable punch in said block and having spaced dies at its lower end adapted to punch two tongues from the overlapped ends of a band supported in said machine, two horizontally, relatively movable members within the block and adapted to move under the overlapped ends of the band, said movable members having cam surfaces, a fixed pin in said block between said members and adapted to be engaged by the cam surfaces on the two members, whereby as the members move under said ends they are pushed apart to turn over the ends of said tongues, and means for operating said punches and movable 45 members.

GEORGE MORTIMER.
